UNITED STATES PATENT OFFICE.

SWITS CONDÉ, OF OSWEGO, NEW YORK.

BURR FOR KNITTING-MACHINES.

SPECIFICATION forming part of Letters Patent No. 240,008, dated April 12, 1881.

Application filed August 13, 1879.

To all whom it may concern:

Be it known that I, SWITS CONDÉ, of Oswego, in the county of Oswego, in the State of New York, have invented new and useful 5 Improvements in Burrs for Knitting-Machines, of which the following, taken in connection with the accompanying drawings, is a full, clear, and exact description.

This invention relates to the feed mechanism 10 of a knitting-machine designed to knit fabric with a vertical or longitudinal stripe, and has more particularly reference to that class of the aforesaid mechanism in which two loop-wheels or so-called "burrs," fed with separate threads, 15 operate side by side, one of said burrs being of the ordinary construction and filling every needle with thread, while the other has a certain number of the interstices between its thread-lifting teeth or wings filled with a block 20 which presses against and closes the beards of certain needles, and thus causes its thread to skip over the said needles, carrying the single thread applied thereto by the other aforesaid burr.

25 The invention consists in truncating the hook ends or nibs of the wings or teeth adjacent to the filled interstices in the periphery of the burr, which press against and close the beards of the needles, by the removal of which 30 hooks or nibs the thread or yarn is relieved of all upward strain and allowed to pass straight across the front of the needle or needles, and thus leave a smooth surface at the back of the fabric.

35 The invention is fully illustrated in the accompanying drawings, wherein Figure 1 is a side view of that part of a knitting-machine to which my improvement is applied. Fig. 2 is a detached view of the knitting-needle and 40 that part of the burr which causes the dropping of the stitch or loop. Fig. 3 is a plan view of the aforesaid burr, and Figs. 4 and 5 are detached side and end views, respectively, of the devices applied to the said burr for the 45 attainment of the object of my invention.

Similar letters of reference indicate corresponding parts.

Represents the horizontally-revolving drum or rim of a rotary knitting-machine, upon which 50 are secured vertically the bearded needles *nn*,

having at the upper end a hook the free end of which projects downward on the outer side of the needle.

B is the loop-wheel or so-called "burr," which forces the yarn into the hooks of the needles *nn*, and thus makes the first step toward the formation of a mesh or loop. This burr ordinarily consists of a cylinder provided on its periphery with wings *a a*, arranged oblique to the line of the axis of the cylinder, and springing from the rear end of the cylinder with a uniform curvature, and terminating at the front ordinarily with an outward-projecting hook or nib, *b*. The burr is mounted on an inclined spindle which is arranged outside of 55 the rim or drum C, and in such position as to cause the wings *a a* to enter between the needles *nn* on the horizontally-revolving drum C. The rotation of said drum causes, by the engagement of the needles with the wings of the 60 burr, the latter to revolve. The yarn, being passed between the needles and the burr, is thus pressed against the needles, and by the nibs *b* of the wings *a* carried up and into the 65 hooks of the needles. A revolving disk, A, 70 bearing upon the knitted fabric near its junction with the needles, presses the previously-formed loops down below the hooks of the 75 needles before the entrance of the yarn, as before set forth. A horizontal disk at the opposite side of the burr, pressing against the 80 free ends of the hooks, closes the same and allows the meshes at the bottom of the needles to slip up over the outside of the hooks, and, by the usual landing-burr and knocking-over 85 burr, be carried over the tops of the needles, and thus complete the new loops or meshes with the yarn in the needles.

In my invention two threads or strands of 90 yarn are fed separately to the machine by two burrs arranged in close proximity to each other, and in such position relative to the auxiliary knitting mechanism that both threads or yarns may enter the needles before the meshes previously formed on the fabric are drawn over 95 them. One of said burrs being of the ordinary construction, as before described, fills every needle and produces continuous stitches, the other extra burr having the hook or nib *b* of one or more of the wings truncated and the 100

space at the side of said wing partly filled by a cam-shaped block, *c*. The pressure of the block *c* against the free end of the hook of the needle closes the same and prevents the yarn fed to said burr from entering it, and the truncation of the nib *b* allows the thread to pass freely and straight over the outside of the needle. The aforesaid ordinary burr fills with its single thread the needles which were skipped 5 and left empty by the other mutilated burr, and then the mesh which is at the bottom of the needle being drawn up over the said thread, as before described, forms a new mesh with the same, leaving the thread of the mutilated 10 burr free on the exterior of the fabric. The latter loose thread is combined with the other continuously-entering thread by the hooked wings of the mutilated burr carrying the loose thread into the hooks of the needles containing the thread fed by the ordinary burr before the previously-formed meshes are drawn over them.

It will be observed that, by using a different color of yarn with each of the said burrs and arranging the burrs so that the truncated wings 15

will operate on the same needles at every revolution of the needle-carrying rim or drum *C*, vertical stripes are produced in the fabric, the meshes of the single thread forming plain-colored stripes and those of the double thread 20 producing mottled stripes.

Having thus described my invention, what I claim as new, and desire to secure by Letters Patent, is—

The loop-wheel or burr *B*, provided with a 25 series of hooked wings, *a b*, a series of wings without such hooks, and the filling-blocks *c*, arranged between the said two series of wings, substantially as described, and for the purpose set forth.

In testimony whereof I have hereunto signed my name and affixed my seal, in the presence of two attesting witnesses, at Oswego, in the county of Oswego and State of New York, this 25th day of July, 1879.

SWITS CONDÉ. [L. S.]

Witnesses:

FRED L. CONDÉ,
EDWD. MAXWELL.
